PEDESTAL TABLE WITH PIVOTED DROP LEAF AND FOLDING BASE

Henry E. English, Tampa, Fla.

Application May 28, 1946, Serial No. 672,798

1 Claim. (Cl. 311—96)

1

This invention relates to furniture, and more particularly to tables, susceptible of numerous and varied uses, where it is desirable to change the size to meet the desired conditions, or in other words, tables susceptible of wide use including, for example, in limited living quarters where space is at a premium, as well as a table which may be easily transported.

Heretofore when it was desirable to have the benefit of several types of tables in the home, such as a dining table, a card table, an ironing board, or the like, it was necessary to have one of each, resulting in a relatively large amount of space being occupied by tables either in use or not, with an outlay proportionate to the number required. Furthermore, many folding tables which have been available are of poor unsubstantial design, having too limited a use, are difficult to manipulate and even when folded have protruding members which provide undesired obstacles.

It is an object of this invention to provide a folding table having a drop leaf table top pivotally supported by a single pedestal with a folding base, in order that the entire structure may be folded into substantially one plane.

Further objects and advantages of the invention will be apparent from the following description, taken in conjunction with the accompanying drawings, wherein:

Fig. 1 is a perspective view of the table as it appears when set up for use;

Fig. 2, a perspective view of the table as it appears when partially folded;

Fig. 3, an elevation of the table, when folded, viewed along the plane of the table top; and,

Fig. 4, a modified construction illustrating an alternate means of affording support for the drop leaves.

With continued reference to the drawings, a table top 10 is provided with drop leaves or additional surface members 11 pivotally attached to the table top 10 by hinges 12 and adapted to be supported in the same plane as the table top 10 by pivoted members 13 attached to said table top. A supporting member or pedestal 14 is pivotally attached to the table top by hinge 15.

Rigidly attached to the pedestal 14 and resting in a notch 14' in the pedestal is a supporting rod 16 adapted to rest against the under side of the table top when the table is in the position to be used, to provide additional support.

A transverse member forming two outriggers or feet 17 is rigidly attached to the lower extremity of the pedestal 14, and a pair of addi-

2

tional outriggers 18 are pivotally attached by hinges 19 to the intermediate portion of the members forming feet 17. Spring latches 20 attached to each of the outriggers 17 are adapted to cooperate with catches 21 attached to each of the outriggers 18 to hold outriggers 18 perpendicular or crosswise of outriggers 17. A spring latch 22 attached to the under side of the table top 10 is adapted to cooperate with the catch 23 attached to the pedestal 14 when the plane of the table top 10 is perpendicular to the pedestal 14, to prevent the table top 10 from pivoting about the hinge 15.

In order to secure the table top in a plane substantially parallel with that of the pedestal, a projection 24 attached to the underside of the table top 10 is adapted to engage a clip 25 attached to the pedestal 14.

For the purpose of holding the drop leaves 11 back against the table top 10, as shown in Fig. 3, members 26, having declivities 28, adapted to rotate about pins 27, affixed to table top 10, are provided to engage hooks 29 attached to the underside of drop leaves 11.

25 Referring to the modification shown in Fig. 4, sliding bolts 30 are adapted to be positioned and supported by channel members 31 and 32 which are affixed to the underside of the table top 10 and drop leaves 11. The sliding bolts 30 are adapted to support the drop leaves 11 when it is desired to use said drop leaves to provide additional table surface. Projections 33 are affixed to the underside of table top 10 to limit the retraction of sliding bolts 30 by acting as stops thereto.

30 Thus the invention discloses a table of general utility designed to be used satisfactorily as a utility table for dining, card-playing, ironing, writing, and the like, which may be economically made and which may be folded to occupy a very small space. While we have illustrated one particular form of the invention it is obvious that changes and adaptations may be made thereto within the scope of the following claim without departing from the spirit, purpose, and intent of the invention.

35 What is claimed is:
 A folding table comprising an elongated upright pedestal, a table top having an elongated intermediate section centrally pivoted to the top of said pedestal adjacent one edge thereof, a pair of elongated leaves hingedly connected to the longitudinal edges of said intermediate section, a rod rigidly secured in a recess formed in the top 40 of said pedestal and extending transversely of said

intermediate section to provide additional support therefor, a plurality of elongated members centrally pivoted on the underside of said table top adjacent the longitudinal edges thereof, said members being movable to a position supporting said leaves in extended position, a hook member on the underside of each of said leaves and cooperating members pivotally mounted on the underside of said intermediate section engageable with said hook members for retaining said leaves in folded position, a catch mounted on the upper portion of said pedestal opposite said pivotal connection and a spring latch mounted on the underside of said intermediate section for engagement with said catch to retain said intermediate section in opened position, a projection attached to the underside of said intermediate section adjacent one end thereof and a clip attached to an intermediate portion of said pedestal for engagement with said projection to retain said intermediate section in folded position against said pedestal, a pair of feet extending in opposite directions from the bottom of said pedestal, an outrigger pivoted to each of said feet adjacent said pedestal and movable from a position beside said feet to a position perpendicular to said feet, and fastening means on said feet and said

outriggers for retaining them in perpendicular position.
